DEVICE FOR REMOTE CONTROL

Gábor Kornél Tolnai, Stockholm, Sweden, assignor to Aktiebolaget Gerh. Arehns Mekaniska Verkstad, Stockholm, Sweden, a joint-stock company of Sweden

Application March 4, 1940, Serial No. 322,221
In Sweden March 1, 1939

4 Claims. (Cl. 172—239)

This invention relates to devices for remote control, such as transmission or controlling of angular or rotary movements, and it is an object of the invention to provide an improved device for remote control of angular positions of an indicator, pointer, crank or the like or a gun or for correcting undesired differences of relative rotary movements of members such as rotary parts of machines.

In the accompanying drawing:

Fig. 1 illustrates diagrammatically an embodiment of the device for the control or transmission of movements;

Fig. 2 is a diagrammatic view of part of the device;

Fig. 3 is a diagrammatic view illustrating angular displacement of part of the device; and

Fig. 4 is a longitudinal side view of the same part of the device.

Referring to the drawing, a transmitter is provided with a rotary journaled shaft 1 the rotary movements of which are to be transmitted to a receiver. The shaft 1 can be rotated or turned by means of a crank 3. The transmitter has an electric voltage distributor or regulator 2, rigidly mounted on the shaft 1 and provided with a plurality of slip rings 4 which are insulated from each other. The rings 4 are electrically connected each to a distributor segment 5, which segments are insulated from each other and mounted on a flange 6 of the distributor 2. A contact brush 7 engages each slip ring 4. One of said brushes is earthed and the other brushes are connected to sources of electric currents of different voltages. Thus the brushes carry currents of 0, 4, 8, 12 and 16 volts, in which case the voltage in the contact segments are in succession 0 volt, 4 volts, 8 volts, 12 volts and 16 volts, respectively. The segment 60 is non-conducting. Coaxially with the distributor 2 is rotatably mounted a brush holder 8 which is driven by a synchronous motor 9. The brush holder 8 is provided with two slip rings 12 which are electrically insulated from each other and electrically connected each to one of two oppositely disposed contact brushes 10. During the rotary movement of the brush holder 8 the brushes 10 move in a circular path over the contact segments 5 of the distributor 2 and engage them, so that they are successively caused to establish electric connection with segments 5 of stepwise increasing or decreasing voltages unless the voltage distributor 2 has exactly the same rotary velocity as the brush holder 8. The brushes 10 are by means of their respective slip rings 12

electrically connected each to one of two contact brushes 11 that form terminals of electric conductors.

The receiver with its voltage distributor, brush holder, brushes etc. is in the present embodiment of the invention exactly similar to the transmitter. Thus, the receiver has a voltage distributor or regulator 13 that operates with corresponding voltages, such as 0, 4, 8, 12 and 16 volts, supplied through contact brushes 7. To the distributor 13 is connected the member (not shown) the movement or position of which is to be controlled. Corresponding brushes 11 and 15 of the transmitter and receiver, respectively, may for that purpose be connected to one and the same source of current. Exactly corresponding voltages are, however, not necessary, but they may differ slightly. A difference of 0.2 volt may be permissible. The brush holder 14 of the receiver coacts with brushes 15 and is driven by the synchronous motor 16. The brushes 10 rotate in the direction indicated by the arrows in Fig. 2. The brush 10s' of the transmitter is connected by an electric conductor to the brush 10m' of the receiver, and the other brush 10s'' is connected by another electric conductor to the other brush 10m'' of the receiver. The motors 9 and 16 are driven synchronously and connected to a joint electric circuit which is connected to a transformer 61.

The voltage distributor 13 is rotatably connected by means of a gear 17, 18 to a driving shaft 19, which is connected by means of a reversing gear 20 to a shaft 21 on which is rigidly mounted a ratchet wheel 22. The ratchet wheel 22 is connected by means of an overrunning clutch 25 to the shaft 24 of a motor 23. The reversing gear 20 is controlled by a lever 27 which is pivoted on a pin 26 and movable between two electromagnets 28 and 29. The electromagnets 28 and 29 are connected to a source of current 30, and their circuits can be alternately closed and broken by an armature 31 arranged between two polarized magnets 32 and 33 the coils of which are connected to the conductors that interconnect the brush holders 8 and 14.

The ratchet wheel 22 coacts with a spring loaded pawl 35 that is controlled by an electromagnet 34. The coil of the electromagnet 34 is connected to a source of current 36, and its circuit is connected to electric control members such as relays 37 and 38 which are connected each to one of both the conductors that interconnect the brushes 10s', 10m' and 10s'', 10m'', respectively.

If the voltage distributors 2 and 13 of the transmitter and receiver, respectively, occupy the positions of equilibrium shown in Fig. 2 none of both the conductors that interconnect the brushes 11 and 15 carries any current as no difference of potential exists between the brushes connected to one and the same conductor. They have the same voltage, such as 0 and 16 volts, respectively. Now, if the shaft 1 and thereby the voltage distributor 2 is turned from the position of equilibrium the terminal voltages of the brushes 11 and 15 will be different at the transmitter and receiver, as they engage contact segments 5 of different voltages. Then the conductors carry current through the relays 37 and 38 which close the circuit through the electromagnet 34, so that the latter retracts the pawl 35 which then releases the ratchet wheel 22. Then the sliding in the clutch 25 ceases, i. e. the motor 23 starts driving the shaft 21, which takes place rapidly and at a considerable turning moment. As long as the brushes 10 of the transmitter and receiver engage contact segments of different voltages the pawl 35 is maintained retracted, and the shaft 19 rotates the distributor 13 of the receiver. As shown in Fig. 2, the brushes 10 and the contact segments 5 are disposed in such manner that only one of a pair of brushes 10 can touch a voltage carrying segment. If, for instance, the distributor 2 of the transmitter has been displaced in the direction of the arrow (Fig. 3) slightly (less than the width of a segment 5) into the dash and dot position a difference of voltage is present at both the brushes 11 and 15, connected to one and the same conductor merely during the intervals at which both the brushes 10s' and 10s'' move from A (in full lines) to B (in dash and dot lines). During the intermediate intervals the conductors between the brushes 11 and 15 carry no current and the magnet 34 releases the pawl 35 which is instantaneously moved by a spring into locking position to arrest the wheel 22 and thereby also the shaft 13. Thus the shaft 19 and the voltage distributor 13 of the receiver move with very short and rapid steps until the distributor 13 by rotation in a clockwise direction has obtained the position shown in Fig. 3 in dash and dot lines, and thereby synchronism has been obtained. The locking means is accommodated in such manner that the ratchet wheel 22 performs at each current impulse a very rapid rotary displacement through one pitch of teeth. This minimum of movement represents the accuracy of the device.

If the shaft 1 of the transmitter together with the distributor 2 have been displaced angularly in a direction opposite to that shown by the arrow in Fig. 2 the distributor 13 of the receiver has obviously to be turned rearwards. Then the shaft has obviously to rotate in a direction opposite to that required to overtake a lead. But the shaft 21 has always one and the same rotary direction. Therefore the gear has to reverse the rotary direction of the shaft 19 in dependence of the direction of the relative angular displacement of transmitter and receiver.

This can be effected by means of the polarized magnets 32 and 33 and suitable relative arrangement of the conducting and non-conducting contact segments of the voltage distributors. If, for instance, the distributor 2 has been displaced angularly relative to the distributor 13 in the direction of the arrow (Fig. 2) through one step, corresponding to the circumferential width of

one segment 5, the conductor connecting the brushes 10s'' and 10m'' carries a current, while the conductor connecting the brushes 10s' and 10m' is dead. If the relative angular displacement is directed reversely the conductor connecting the brushes 10s' and 10m' carries a current, while the conductor connecting the brushes 10s'' and 10m'' is dead. Thus, the armature 31 is attracted by the magnet 32 or the magnet 10 33 in dependence of the direction of the relative angular displacement, and, consequently, the coil of either the magnet 23 or the magnet 29 will be energized in dependence of the said direction of displacement. Thus the reversing gear 20, i. e. the rotary direction of the shaft 19, will be controlled in dependence of the direction of the relative angular displacement of transmitter and receiver. This is effected in such manner that the shaft 19 imparts to the distributor 13 a forward or rearward rotary movement, if the shaft 1, i. e. the crank 3, has been turned forward or rearward, respectively, relative to the distributor 13.

In the embodiment now described the device 25 has been assumed to transmit variations of movement from an angularly adjustable member (e. g. a crank or pointer) to another member (e. g. a pointer), but the invention is not limited to this embodiment. The distributors of the transmitter and receiver may, for instance, be adapted to rapidly correct undesired phase displacements. As long as both the voltage distributors revolve at exactly the same speed, the magnet 34 receives no electric impulses, but as soon as 30 a phase displacement occurs, the shaft 19 will start rotary movement and correct the error as described. It is not necessary, however, that the brush holders 8 and 14 revolve. They may be immovable, if the distributors rotate, so that 35 a relative movement of the contact segments 5 and brushes 10 is obtained.

I claim:

1. A device for transmission of angular or rotary movements, comprising a transmitter, a receiver, an electric conduit for interconnecting said transmitter and said receiver, said transmitter and said receiver each having a voltage distributor comprising a series of contact members, a series of sources of electric current of stepwise increasing voltages each connected to one of said contact members to supply said contact members with electric current of successively and stepwise increasing voltages, said series of contact members consisting of a plurality of 45 juxtaposed segments which are isolated from one another and form a curved contact bridge, a non-conducting field between the ends of said curved bridge, said series of contact members in said transmitter and in said receiver being arranged in similar sequences with respect to their voltages and having substantially corresponding voltages respectively, said transmitter and said receiver each having a collecting contact member forming terminals of said conduit and being adapted to electrically interconnect said sources of electric current and said electric conduit, means for relatively rotating the distributor and collecting member of said transmitter and said receiver, mechanical means for driving the receiver, and electro-magnetic means connected to said conduit to control said driving means.

2. A device for transmission of angular or rotary movements, comprising a transmitter, a receiver, an electric conduit for interconnecting said transmitter and receiver, said transmitter

and said receiver each having a voltage distributor comprising a series of contact members, a series of sources of electric current of stepwise increasing voltages each connected to one of said contact members to supply said contact members with electric current of successively and stepwise increasing voltages, said series of contact members consisting of a plurality of juxtaposed segments which are isolated from one another and form a curved contact bridge, a non-conducting field between the ends of said curved bridge, said series of contact members in said transmitter and in said receiver being arranged in similar sequences with respect to their voltages and having substantially corresponding voltages respectively, said transmitter and said receiver each having a collecting contact member forming terminals of said conduit and being adapted to electrically interconnect said sources of electric current and said electric conduit, and means for relatively rotating the distributor and collecting member of said transmitter and said receiver, mechanical means for driving the receiver, and electro-magnetic means connected to said conduit to control said driving means, said electro-magnetic means comprising polarized electromagnets adapted to reverse the rotary direction of said receiver.

3. A device for transmission of angular or rotary movements, comprising a transmitter, a receiver, two electric conduits for interconnecting said transmitter and receiver, said transmitter and said receiver each having a voltage distributor comprising a series of contact members, a series of sources of electric current of stepwise increasing voltages each connected to one of said contact members to supply said contact members with electric current of successively and stepwise increasing voltages, said series of contact members consisting of a plurality of juxtaposed segments which are isolated from one another and form a substantially semi-circular contact bridge, another semi-circular bridge interconnecting the ends of said contact bridge and having a non-conducting bridge which is juxtaposed to the 45

- contact member of the highest voltage and a conducting segment juxtaposed to the contact member of the lowest voltage, said series of contact members in said transmitter and in said receiver being arranged in similar sequences with respect to their voltages and having substantially corresponding voltages respectively, said transmitter and said receiver each having two collecting contact members forming terminals of said conduits, means for relatively rotating said distributors and collecting members of said transmitter and said receiver to alternatively establish through said conduits electrical connection between said sources of electric current and said contact members, and electromagnetic means connected to said conduits to control the rotation of the distributor of the receiver.
4. A device for transmission of angular or rotary movements, comprising a transmitter, a receiver, an electric conduit for interconnecting said transmitter and receiver, said transmitter and said receiver each having a voltage distributor comprising a series of contact members, means for rotating the distributor of the transmitter, means for rotating the distributor of the receiver, a series of sources of electric current of stepwise increasing voltages connected each to one of said contact members to supply said contact members with electric current of successively and stepwise increasing voltages, said series of said contact members in said transmitter and in said receiver being arranged in similar sequences with respect to their voltages and having substantially corresponding voltages respectively, said transmitter and said receiver each having a collecting contact member each forming a terminal of said electric conduit and being adapted to electrically interconnect said sources of electric current and said electric conduit, means for driving said collecting contact members to rotate synchronously, and electromagnetic means connected to said conduit to control the driving means of the receiver distributor.

GÁBOR KORNÉL TOLNAI.
